UNITED STATES PATENT OFFICE.

DAVID HOUSTON McKELLAR, OF MOTHERWELL, SCOTLAND.

FINGER-RING.

1,309,647.

Specification of Letters Patent. Patented July 15, 1919.

Application filed November 8, 1918. Serial No. 261,669.

To all whom it may concern:

Be it known that I, DAVID HOUSTON Mc-
KELLAR, of 34 Brandon street, Motherwell,
Scotland, have invented certain new and
useful Improvements in and Connected with
5 Finger-Rings, of which the following is a
specification.

My invention relates to improvements in
and connected with finger rings of the kind
10 where two different emblems or designs can
be exposed at separate times, by the move-
ment of the center or signet part and has
for its object to provide one of a very simple
and efficient nature.

15 In carrying out the invention, I provide
a suitable slide working in a guide formed
in the upper part of the ring. Carried on
this slide is the center or signet part of the
ring on each side or face of which the em-
20 blems or designs are engraved, carved or
otherwise placed.

When it is desired to reverse the emblem,
the hinged end of the center or signet part
is depressed, when the other end rises. It
25 is then gently pulled along with the slide to
the opposite side of the ring and then turned
down when the other emblem or design is
exposed.

As a slightly modified form of carrying
30 out my invention, the guide is in the form
of a slot or cut-out in the center portion of
the upper part of the ring, in which the
slide, which is in the form of a small pin
suitably hinged or pivoted to the center or
35 signet part of the ring, works. At each end
of the slot or cut-out there is a small piece
which engages a small cut-out at each end
of the signet part, and so locks when in po-
sition, or a small pin on the side of the cen-
40 ter position of the ring engaging a small
hole in the signet part effects the same ob-
ject. In this case, when it is desired to re-
verse the emblem or design, the lock is re-
leased and the center or signet part is raised
45 up. It is then pulled gently along the guide
till it reaches the end thereof, when it is
pressed down and becomes locked, the other
emblem or design being then exposed.

In order that my invention may be prop-
50 erly understood and readily carried into ef-
fect, I have hereunto appended one sheet of
drawings, of which

Figure 1 is a plan view of a finger ring
made in accordance with and embodying
55 my invention.

Fig. 2 is part a side elevation and part

vertical section of the same, both of which
figures are drawn to an enlarged scale.

Fig. 3 is a further vertical section of part
of the ring drawn to a further enlarged 60
scale.

Fig. 4 is a view corresponding to Fig. 1
of a modification of the improvements.

Fig. 5 is a part elevation and part vertical
section of the same and corresponding to 65
Fig. 2 drawn to an enlarged scale, and

Fig. 6 is a further vertical section of part
of the same ring drawn to a further enlarged
scale, and corresponding to Fig. 3, all here-
after more fully referred to and described. 70

Referring to Figs. 1 to 3 inclusive, the
signet portion of the ring is provided with
a rectangular shaped recess A, the two op-
posite edges of said recess having undercut
surfaces A¹, A². The edges of the recess A 75
and the undercut surfaces A¹ and A² form
guides for the movement of a hinge slide B.
Pivoted or hinged to this slide is the rec-
tangular shaped plate C constituting the
signet portion of the ring which, in its nor- 80
mal position, occupies the recess A. The
upper surface B¹ of the plate C represents
one design, and the opposite or undersurface
B² represents another design. To change
the design, the plate B is tilted up into the 85
position shown in Figs. 2 and 3, when it is
slid along to the position in dotted lines,
Fig. 2, and pressed down.

Referring to Figs. 4 to 6 inclusive, a cen-
tral slot E cut transversely in the signet por- 90
tion of the ring takes the place of the recess
and undercut surfaces already referred to.
Working in the said slot E is a hinge slide
F provided with a projection stud or head G
which keeps the slide from dropping out of 95
the slot. Pivoted or hinged to said slide F
is the elliptically shaped plate H which con-
stitutes the signet member of the ring. The
two flat surfaces H¹ and H², of the plate
have each a different design or emblem en- 100
graved or otherwise delineated thereupon.
The method of presenting the design im-
pressed on the one face of the signet, and
reversing it in order to show the other de-
sign, is similar to that already described 105
with reference to Figs. 1 to 3. A small pin
or projection I is mounted on the center of
the ring and the function of the pin is to
coact and engage with a small hole J formed
in the plate H in either of the two normal 110
positions thereof and this insures stability
and the requisite retention of the parts.

It is to be understood that my improvements are also applicable to scarf-pins, scarf-rings, and pendants.

Claims:

- 5 1. A signet ring formed with a recess upon the signet portion of said ring, undercut surfaces constructed at opposite points of such recess in order to constitute guides or guide surfaces, a hinge slide adapted to 10 move in such guides or surfaces, a plate pivoted or hinged to said hinge slide in order to move with said slide when tilted up and capable of being pressed down into a reverse or inverted position in order to present 15 one or the other of two signet devices or emblems represented on the two sides of a signet plate, substantially in the manner and for the purposes hereinbefore described and shown on the drawings.

2. A signet ring formed with a central slot 20 in order to constitute guides or guide surfaces, a hinge slide adapted to move in such guides or surfaces, a plate pivoted or hinged to said slide in order to move with said slide when tilted up and capable of being pressed 25 down into a reverse or inverted position in order to present one or the other of two signet devices or emblems represented on the two sides of a signet plate and the means of locking same, substantially in the manner and for the purposes hereinbefore described and shown on the drawings.

In witness whereof I affix my signature in presence of two witnesses.

DAVID HOUSTON MCKELLAR.

Witnesses:

JOHN LIDDLE,

JOHN TRAIN LIDDLE.
